MECHANISM FOR USE IN ATTACHING SHANK-PIECES TO SHOES.

1,399,732.

Specification of Letters Patent.

Patented Dec. 13, 1921.

Application filed March 23, 1918. Serial No. 224,179.

To all whom it may concern:

Be it known that we, FRED L. AYERS and FRED L. MACKENZIE, citizens of the United States, residing at Everett, in the county of Middlesex and State of Massachusetts, and Beverly, in the county of Essex and State of Massachusetts, respectively, have invented certain Improvements in Mechanism for Use in Attaching Shank-Pieces to Shoes, of which the following description, in connection with the accompanying drawings, is a specification, like reference characters on the drawings indicating like parts in the several figures.

15 This invention relates to mechanism for use in operating on shoes to which shank pieces are attached and is particularly designed for application to a fastening inserting machine adapted to tack the shank pieces 20 to the shoes.

In the manufacture of certain kinds of shoes, it is customary to attach to the shank portion of the insole of a shoe, prior to the laying on of the outsole, a shank piece calculated to strengthen the shank of the shoe 25 and to improve the appearance of the shoe.

The shank piece is commonly reinforced by a metal strip applied to the under side of the shank piece and extending lengthwise 30 of the shank piece along substantially its median line and, in the finer grades of shoes, is molded from rubber or composition and is relatively stiff and inflexible so as to retain 35 its shape under the pressure exerted by the outsole laying machine. The shank piece facilitates the production of the desired exterior contour and appearance of the tread surface of the shoe by reason of the molding of the outsole by the sole laying machine 40 over the convexly curved outer surface of the shank piece. To the end that the shoe may be durably constructed and symmetrically formed, it is essential that the plane surface of the shank piece at the forward end of the 45 shank piece be accurately alined with the surface of the insole forwardly of the shank piece as otherwise a space will be left in the finished shoe either between the outsole and the surface of the shank piece or between the outsole and the insole adjacent to the shank piece, depending upon whether the plane surface of the shank piece is disposed inwardly or outwardly of the plane of the surface of the insole. In either case, it will

be seen that the outsole will not present the 55 smooth and even appearance which is very desirable in high grade shoes and that the wearing qualities of the shoe will be impaired by reason of the outsole not being properly sustained at all points. 60

In the manufacture of shoes in which shank pieces of the kind above described are used, the outsole is molded to substantially the shape which it will have in the finished shoe previous to its application to the shoe, 65 there being formed in the outsole in the molding operation, a well-defined angle marking the break line between the shank portion and the forepart of the outsole. Before the outsole is laid on the shoe, the 70 surface of the insole and shank piece and the inner surface of the outsole are coated with cement which retains the outsole in position until the permanent attachment of the outsole to the shoe. When the outsole is 75 applied to the shoe the break line of the outsole should coincide with the line of meeting of the outer surface of the body of the shank piece with the plane surface at the forward end of the shank piece hereinafter 80 for convenience of description termed the "break line of the shank piece," but by reason of the break line of the shank piece being concealed by the outsole as it is laid on the shoe and inasmuch as the cement prevents movement of the outsole relatively to the insole and shank piece after it is placed thereon, it is difficult for the operator to locate the outsole exactly, with the result 85 that a large proportion of the outsoles are 90 not properly positioned. It is apparent that if the outsole is not applied to the insole and attached shank piece in such manner that the break line of the outsole coincides with the break line of the shank piece, the pressure 95 exerted by the sole laying machine on the outsole will form a crease in the outsole at the point where it lies over the break line of the shank piece greatly injuring the appearance of the shoe. 100

In the present shop practice, the operator applies the shank piece to the shank portion of the insole and presents the work to the throat piece of a tacking machine, inserting a tack through the rear portion of the shank piece and into the insole at one side of the metal strip of the shank piece and then shifts the shoe relatively to the throat piece 105

and inserts a tack through the shank piece at the other side of the metal strip. In doing this work, the operator relies upon his eyes to determine the proper position of the shank piece with the result that the shank pieces are very frequently attached to the shoes in such wise that the surface of the shank piece projects too far outwardly or lies too far inwardly from the surface of the insole with consequent lack of support to a portion of the outsole when it is applied to the insole. The irregular location of the shank pieces adds to the difficulty of properly matching the break line of the outsole with the break line of the shank piece. Moreover, if the shank piece has not been properly applied to the insole, the matching of the outsole with the shank piece so that the break line of the outsole coincides with the break line of the shank piece causes the outsole to be improperly located relatively to the body of the shoe.

An object of this invention is to provide means whereby the defects arising from present methods of applying the shank pieces may be obviated and the shank pieces invariably positioned on the shoe with the surfaces of the shank pieces appropriately related to the surface of the insole and with the shank pieces uniformly located on the shoe so as to facilitate the application of the outsole.

To this end, an important feature of the invention consists in the combination with mechanism for operating on a shoe having a shank piece loosely superposed thereon, of means mounted on the frame which carries said mechanism for positioning the shank piece relatively to said mechanism. Preferably, and as shown, the member which engages the shank piece is formed with surfaces angularly related to each other in such a manner as to engage the shank piece at each side of the break line of the shank piece.

It has been determined by experiment that as regards shoes of the same size and like styles, the distance from the back of the shoe to the break line of the insole is substantially constant. It results, therefore, that, if shoes of like size and like styles are presented to the fastening inserting machine with the backs of the shoes located at a certain predetermined distance from the shank piece positioning means, the shank piece, the location of which is determined by the shank piece positioning means, will invariably be accurately placed on the shoe. Accordingly, another feature of the invention resides in the combination with means for positioning a shank piece loosely superposed on a shoe, of means for positioning a shoe so that the shank piece will be properly located on the shoe.

65 In order that the invention may be con-

veniently employed in the manufacture of shoes of different sizes and styles the shoe positioning means, in accordance with a still further feature of my invention, is made readily adjustable relatively to the shank piece positioning means, and means are provided for indicating the proper position of the shoe positioning means for operation upon a shoe of any size and style.

The invention also contemplates the arranging of the shoe positioning member in such manner as to enable the operator to present the shoe in proper position with relation to the shank piece positioning means and the fastening inserting mechanism with the greatest possible ease and quickness. Accordingly, the shoe positioning member is mounted for movement in a vertical plane and is normally positioned below the plane of the fastening inserting mechanism in full view of the operator and in such location that the operator can engage the shoe therewith without obstruction. After engagement of the shoe with the shoe positioning member, said member is moved upwardly by the shoe in the presentation of the work to the fastening inserting mechanism. Preferably and as shown, for the purpose of expediting the presentation of the work to the fastening inserting mechanism, means is provided for maintaining the shoe engaging surface of the shoe positioning means in substantially the same horizontal plane in different adjusted positions of the shoe positioning means.

The invention also contemplates the mounting of devices on the frame of the fastening inserting machine constructed and arranged to position the shank piece at its rear end and to support the shank piece independently of the shoe in a position determined by the shank piece positioning means.

It is recognized that the invention is not limited to the particular embodiment thereof herein described and illustrated or to operation on shank pieces of the special form described; for example, certain features of the invention are applicable to the attachment of relatively light shank pieces such as are used in the cheaper grades of shoes and which do not have a defined break line. It is intended therefore that the scope of the invention shall be limited only by the language of the appended claims.

Other objects and features of the invention will appear as the description proceeds.

In the drawings,—

Figure 1 is a view of a fastening inserting machine having one embodiment of the invention applied thereto;

Fig. 4 is a view of a shoe with a shank piece attached thereto in the manner contemplated by this invention and of the device for supporting the shank piece.

Fig. 5 is a perspective view of a shank piece, and

Fig. 6 is a view in cross-section on the line 6—6 of Fig. 4.

The invention will be described, by way of example, as applied to a fastening inserting machine of the type disclosed in United States Letters Patent No. 1,106,393, granted August 11, 1914 on an application of Fred L. Mackenzie, and reference may be made 20 to said Letters Patent for a complete description of parts not fully described herein. The machine comprises a nozzle or throat-piece 2 through which fastenings pass for insertion into the work, the fastenings 25 being forced into the work by a driver 4 which is reciprocated upwardly and downwardly in suitable guides in the machine frame 6. The illustrated machine is of the class which inserts previously formed fastenings of relatively small size hereinafter sometimes denominated "tacks," and the operation of the machine is controlled by a treadle, not shown, which is operatively connected by a rod 8 to a starting and stopping mechanism denoted by the reference numeral 10, Fig. 1. The above described parts constitute in themselves no part of the present invention and are fully set forth in the Letters Patent above referred to, for 35 which reason a fuller description thereof is deemed unnecessary. Although the invention is described in its application to a machine for attaching shank pieces to shoes by metallic fastenings, it is to be understood 40 that the invention in its broader aspects is not limited to any particular form of shank piece attaching means.

In the use of the machine a shank piece 12 is secured to the insole of a shoe 14 by 50 means of tacks 16 and 18, Fig. 4, driven through the shank piece near its rear end and at either side of the metal strip 20 which serves to reinforce the shank piece.

As above stated, it is desirable that the 55 shank pieces be properly and uniformly positioned relatively to the soles of the shoes and to the point of insertion of the fastenings. To this end, I have mounted on the frame 6 of the fastening inserting machine 60 a shank positioning member 22 adjustably secured to the frame of the machine by bolts 24 passing through slots 26 in the upper end of the shank positioning member.

Adjustably secured to the shank positioning 65 member 22 at its lower end, by means of a

bolt or the like 28, is a gage member 30 which is formed with shank engaging surfaces 32 and 34 angularly related to each other, the shank engaging surface 32 being arranged to engage the plane surface 36 at the end of 70 the shank piece forwardly of the break line 40 of the shank piece and the shank engaging surface 34 being designed for engagement with the curved upper surface 38 of the body of the shank piece 12 adjacent to 75 and rearwardly of the break line 40 of the shank piece. When a shoe with a shank piece superposed thereon is presented in operative relation to the throat piece 2 of the fastening inserting machine, the shank engaging surfaces of the shank positioning member 22 will engage the shank piece and position the same relatively to the insole of the shoe and the throat 2 of the fastening inserting mechanism.

As hereinabove stated, it has been found by experiment that shoes of the same size and of the same or like styles do not differ appreciably in their dimensions from the backs of the shoes to the break line between 90 the shank and forepart of the insole. It follows, therefore, that if means are provided for positioning the backs of the shoes always in the same relation to the shank positioning means when operating on shoes of 95 like size, the shank pieces will be located on the shoes with great accuracy and uniformity. In the illustrated embodiment of the invention, the shoe positioning means comprises a work engaging member 42 carried 100 by the frame 6 of the machine. Since the distance between the back of the shoe and the break line between the shank and the forepart varies in shoes of different sizes, means are provided for adjusting the work 105 engaging member 42 for different sizes of shoes, and means are also provided for indicating the proper position of adjustment of the work engaging member for shoes of any size. Said means comprises a bracket 110 44 in which is journaled a rock shaft 46 carrying an arm 48 upon which the work engaging member 42 is fulcrumed, as indicated at 50, Fig. 3. It will be clear from the foregoing that if the shaft 46 is rocked or 115 oscillated in either direction, the position of the work engaging surfaces of the work engaging member 42 relatively to the throat piece 2 of the fastening inserting mechanism and the shank positioning means 22 120 will be changed. Means is provided for effecting oscillating movement of the rock shaft 46 in the form of an arm 52 fixedly mounted on the end of the rock shaft 46 and extending upwardly therefrom to a point 125 adjacent to the indicator scale 54, which is toothed or serrated at 56 for engagement therewith of a spring pressed trigger 58 carried by the arm 52, the serrations 56 and trigger 58 operating to maintain the arm 130

52 and perforce the rock shaft 46 and work engaging member 42 in any position of adjustment to which they may be moved. As plainly appears from Fig. 2 of the drawings, the indicator scale 54 marks the proper positions of adjustment of the work engaging member 42 for the different sizes of shoes.

It is important that in all positions of adjustment of the work engaging member 42 relatively to the throat piece 2, the work engaging surfaces should lie normally in substantially the same horizontal plane, to the end that the operator may not be inconvenienced by the necessity of observing the position of the member 42 each time work is presented to the machine but may present the work in operative relation to the work engaging member without conscious inspection of said member which he can do by familiarizing himself with the location of the work engaging member, if the normal work receiving position of the member is not materially changed when adjustments are made.

In the present instance of the invention, this is effected by the provision of a spring 60, Fig. 1, which operates against the pin 62 carried by the work engaging member 42 in a direction to urge the work engaging end of the member downwardly, and a cam member 64 extending rearwardly from the bracket 44 in position to be engaged by the pin 62 to limit the downward movement of the work engaging member 42. By reference to Fig. 1, it will be seen that by reason of the pivot 50 of the work engaging member 42 being arranged substantially in the vertical plane of the rock shaft 46, a movement of the arm 52 in either direction from the position illustrated in said figure will tend to move the work engaging member 42 upwardly. It will be further noted, however, that in the position of the parts indicated in Fig. 1 the pin 62 is substantially in line with the lowest point of the cam 64. Since the curvature of the cam member 64 from its lowest point in either direction is greater than the curvature of the path of movement of the pivot 50 about the rock shaft 46, when the work engaging member 42 is moved in either direction from the position shown in Fig. 1, the tendency of the work engaging end of said member to be raised by the bodily movement of said member is countervailed by angular movement of said member 42 on its pivot 50 due to the pin 62 having imparted thereto an upward movement of greater extent than that of the pivot 50.

The bracket 44 is carried by a member 66 slidably mounted in ways 68 extended from the machine frame 6. Means are preferably provided for adjusting the slide 66 and the parts carried thereby in the ways 68 and, as illustrated, such means comprises rack teeth

70 formed on the slide 66 and engaged with the teeth of a pinion stud 72 journaled in ways 68. The slide 66 may be locked in any position of adjustment in the ways 68 by the bolt 74, Fig. 1.

It has been found in practice that the distance between the back of a shoe and the break line between the shank and the forepart of the insole although the same in shoes of like sizes and of like styles, may differ 75 in shoes of different styles though of the same size. It follows, therefore, that if the parts are so related that the indicator 54 which may be called the "size indicator" properly signifies the position of the work 80 engaging member when operating on shoes of a certain style, such size indicator might not mark the proper position of adjustment of said member for shoes of a different style.

By movement of the work engaging member 42, the bracket 44, and the size indicator 54 together in the appropriate direction relatively to the shank positioning means 22 to an extent equal to the amount by which the distance between the back of the shoe and the break line in shoes of the style to be operated upon differs from the distance between the corresponding parts of a shoe of like size of the style for which the parts are set, the size indicator may be made to denote correctly the positions of adjustment of the work engaging member for shoes of the style to be operated upon. Such movement is effected by sliding the bracket 44 in the ways 68, and in order that adjustments 100 for changes in styles may be accurately made the pinion stud 72 carries a finger 76 associated with an indicator 78 which may be termed the "style indicator."

In the use of the mechanism hereinbefore 105 described, a shank piece which may be of the form shown in Figs. 4, 5 and 6 is applied to the shank portion of the insole of a shoe as portrayed in Fig. 4, and the shoe with the shank piece superposed thereon is presented 110 to the throat-piece of the fastening inserting machine in a position such that a fastening may be inserted through the rear end of the shank piece at one side of the metal strip of the shank piece as indicated at 16, Fig. 4. The shoe and the shank piece are then moved together laterally and again presented to the throat-piece of the fastening inserting machine in a position such that a second fastening may be inserted as indicated at 18, 115 Fig. 4. The shoe with the shank piece attached thereto is then according to the usual factory practice, placed on a rack or other device whereby the shoe may be transported to the machine for laying the outsoles 120 thereon.

The shank piece may be presented in proper relation to the throat piece of the fastening inserting machine previous to and independently of the presentation of the 130

shoe thereto, and my invention contemplates the provision of means for facilitating such operations. Preferably, and as illustrated, such mechanism comprises a shank piece 5 supporting device 84 embodying members 86 and 88 constructed and arranged to receive between them a portion of the metal strip of the shank piece which may project beyond the end of the shank piece. The members 86 and 88 are bifurcated (Figs. 4 and 6) and are constructed to yield upon the insertion of the metal strip of the shank piece between them and to engage the strip frictionally in a manner such as to permit 10 ready lateral movement of the shank piece from one tack inserting position to the other but strongly enough to sustain the shank piece adjacent to or in contact with the throat piece of the fastening inserting machine and in engagement also with the shank piece positioning means 22. It will be understood that the shank piece supporting device 84 also operates as a gage to position the shank piece at its rear end and that said 15 device might be relied upon, if desired, as the sole positioning means for the shank piece, the shank piece positioning member 22 being omitted. It is preferred, however, to utilize the member 22 to position the shank piece longitudinally of the shoe and to depend upon the device 84 to support the shank piece and to position the rear end of the shank piece laterally. The shank piece having been placed in position, the shoe is 20 presented to the fastening inserting machine, being accurately positioned by the work engaging member 42. In the operation of the outsole molding machine the sole is positioned relatively to the device which molds 25 the sole and forms the break line in the sole by a gage member which engages with the rear end of the outsole. The gage member is connected with an indicator which may be called the "size indicator." When it is intended 30 to mold soles for shoes of a certain size the gage is moved until the pointer of the indicator which is connected with the gage registers with the corresponding member on the indicator scale. From the foregoing, it will be clear that soles intended for 35 shoes of the same size will be of uniform dimensions from the heel seat end of the sole to the break line. Adjustments for various sizes are made by moving the gage toward 40 and from the mold thus commensurately decreasing or increasing the distance between the heel seat end of the sole and the break line. Shoes of like size but of unlike styles sometimes require soles of different lengths. 45 A second indicator which may be denominated the "style indicator" is therefore provided to mark the extent of adjustment of the gage member and the size indicator necessary to cause the latter to indicate accurately 50 the position of the gage appropriate

to a sole designed for a shoe of a different style from that for which the molding machine has previously been set.

It will be clear from the above that adjustments of applicant's positioning member 55 42 may be made in accordance with the adjustments of the outsole molding machine, applicant's size indicator and style indicator being set correspondingly to the size indicator and style indicator of the molding 60 machine. The distance between the back of the shoe and the break line of the shank piece may thereby be made to bear a determined constant relation to the distance between the rear end of the outsole and the 65 break line of the outsole. The outsoles are made of a length to extend somewhat beyond the backs of the shoes when applied thereto, and since, by the use of the mechanism hereinbefore described inasmuch as the 70 shank pieces are uniformly located the amount of such projection is made constant when the outsole is properly applied to the shoe with the break line of the outsole coinciding with the break line of the shank 75 piece, the operator is enabled to locate the outsole on the shoe accurately and conveniently by holding the outsole right side up in one hand and with the other holding the shoe in upright position and applying it to 80 the outsole with the back of the shoe spaced by the known distance from the end of the outsole. This method of operation possesses very marked advantage over present methods, which involve much more manipulation 85 of the work and in which one of the elements, *i. e.*, the break line of the shank piece, which are relied upon to locate the outsole is rendered invisible in the operation 90 of laying on the outsole. The tendency in 95 laying on outsoles according to the present method is for the operator to feel with the outsole for the break line of the shank piece in order to determine the correct position of the outsole. The cement applied to the 100 parts prevents, however, movement of the outsole on the shoe and thus precludes the 105 positioning of the shank piece in the above manner.

Having fully described the invention, 110 what I claim as new and desire to secure by Letters Patent of the United States is:

1. In a machine of the class described, a frame, fastening inserting mechanism carried by said frame for attaching a shank 115 piece to a shoe, and means mounted on the frame for positioning the shank piece relatively to the fastening inserting mechanism.
2. In a machine of the class described, a frame, mechanism for attaching a shank 120 piece to a shoe which mechanism is mounted on said frame, and a member mounted on said frame and constructed and arranged for engagement with the shank piece adjacent to the break line of the shank piece 125

to position the shank piece relatively to said attaching mechanism.

3. In a machine of the class described, a frame, mechanism for attaching a shank piece to a shoe which mechanism is carried by said frame, and a work positioning member mounted on said frame and having a work engaging portion constructed and arranged to present a surface overlying the 10 surface of the shank piece forwardly of the break line of the shank piece and a second surface angularly related to the first-mentioned surface for engagement with the shank piece to the rear of the break line 15 of the shank piece.

4. In a machine of the class described, a frame, fastening inserting mechanism carried by said frame and work positioning means mounted on said frame in front of 20 the fastening inserting mechanism and having work engaging surfaces angularly related to each other one of which is disposed for engagement with the end surface of a shank piece presented in operative 25 relation to the fastening inserting mechanism.

5. In a machine of the class described, a frame, fastening inserting mechanism carried by said frame, and work positioning 30 means mounted on said frame forwardly of said fastening inserting mechanism and having a work engaging surface arranged substantially at right angles to the line of drive of the fastening inserting mechanism 35 and a second work engaging surface defining an angle with the first-mentioned work engaging surface.

6. In a machine of the class described, a frame constructed and arranged to have a 40 shoe presented thereto for attachment of a shank piece to the shoe, means for positioning the shoe relatively to said frame, and means for positioning a shank piece loosely superposed on the shoe relatively to the 45 frame and the shoe so that the shank piece may be properly located on the shoe.

7. In a machine of the class described, a frame, mechanism for operating on a shoe, such mechanism being carried by the frame, 50 work positioning means mounted rearwardly of the operating mechanism and constructed and arranged for engagement with the back of a shoe in inverted position, and work positioning means mounted 55 forwardly of said operating mechanism and constructed and arranged for engagement with the end surface of a shank piece superposed on the outer surface of the shoe.

8. In a machine of the class described, 60 mechanism adapted to have a shoe presented thereto with a shank piece superposed on the shoe and comprising a frame, shank piece attaching means carried by said frame, shoe positioning means mounted 65 rearwardly of said attaching means and con-

structed and arranged for engagement with the back of a shoe, means for adjusting said shoe positioning means relatively to said attaching means, and mechanism mounted forwardly of said attaching means 70 and constructed and arranged for engagement with the shank piece to position the same.

9. In a machine of the class described, mechanism adapted to have a shoe presented 75 thereto with a shank piece superposed on the shoe and comprising a frame, shoe positioning means carried by said frame and constructed and arranged for engagement with the back of a shoe, and mechanism carried by said frame in spaced relation to said shoe positioning means and constructed and arranged for engagement with a shank piece to position the same relatively to the shoe, said mechanism being adjustable. 80

10. In a machine of the class described, a frame, fastening inserting mechanism carried by said frame, work positioning means mounted on said frame rearwardly of said fastening inserting mechanism and having 90 a work engaging surface arranged substantially at right angles to the line of drive of the fastening inserting mechanism and a work engaging surface arranged angularly to said first-mentioned surface and faced 95 toward the line of drive of the fastening inserting mechanism for engagement with the back of a shoe when in inverted position, and means for positioning a shank piece on said shoe. 100

11. In a machine of the class described, mechanism adapted to have a shoe presented thereto with a shank piece superposed on the shoe and comprising shank piece attaching means, shank piece positioning means, and shoe positioning means comprising a frame, a shoe engaging member carried by said frame, means for adjusting said shoe engaging member in accordance with the size of the shoe being operated upon, and means for indicating the proper position of adjustment of said engaging member for shoes of different sizes to position the shoes in proper relation to the shank piece positioning means. 110

12. In a machine of the class described, a frame, fastening inserting mechanism carried by the frame for attaching a shank piece to a shoe, shoe positioning means constructed and arranged to locate a shoe and a shank piece superposed thereon in operative relation to the fastening inserting mechanism, and having a part constructed for engagement with the upper surface of the shoe upon movement of the shoe to operative position relative to the fastening inserting mechanism, said shoe positioning means being normally positioned below the plane of the fastening inserting mechanism and movable upwardly by the shoe upon 120 125 130

presentation of the shoe to the fastening inserting mechanism, and means for normally urging said positioning means downwardly.

13. In a machine of the class described, 5 a frame, fastening inserting mechanism mounted on the frame, work positioning means mounted on the frame and having a part constructed for engagement with the upper surface of the work upon movement 10 of the work to operative position relative to the fastening inserting mechanism, said work positioning means being normally positioned below the plane of the fastening inserting mechanism and movable upwardly 15 by the work upon presentation of the work to the fastening inserting mechanism, means for normally urging said work-positioning means downwardly, means for limiting the downward movement of the work positioning 20 means, and means for moving the work positioning means relatively to said limiting means in a direction transverse to its upward movement.

14. In a machine of the class described, 25 shoe positioning means comprising a frame, a work engaging member carried by said frame for movement in a vertical plane relatively to said frame, and constructed and arranged for engagement with the side of a 30 shoe, means for adjusting said work engaging member in substantially a horizontal plane, and a cam relatively to which the work engaging member is movable when adjusted for maintaining the work engaging 35 surface of the member normally in substantially the same horizontal plane in different positions of adjustment of the member.

15. In a machine of the class described, 40 work positioning means comprising a frame, a work engaging member pivotally mounted on said frame for movement upwardly and downwardly, means for adjusting said work engaging member in accordance with 45 different characteristics of the work being operated upon, and means relatively to which the work engaging member is bodily movable for controlling the angular movement of the work-engaging member about 50 its pivot so as to maintain the work engaging surface of said member normally in substantially the same horizontal plane is different adjusted positions of said member.

16. In a machine of the class described, 55 work positioning means comprising a frame, a bracket carried by said frame, an arm pivotally mounted on said bracket, a shoe engaging member carried by said arm and movable relatively to said arm in a vertical 60 plane, means for normally urging said shoe engaging member downwardly, and means mounted on the bracket independently of the arm for limiting the downward movement of the member.

17. In a machine of the class described, 65 work positioning means comprising a frame, a bracket carried by said frame, an arm pivotally mounted on said bracket, a shoe engaging member carried by said arm and movable in a vertical plane, means for normally urging said shoe engaging member downwardly, and a cam member rigidly mounted on the bracket for limiting the downward movement of the shoe engaging member. 75

18. In a machine of the class described, 80 work positioning means comprising a frame, a bracket carried by said frame, an arm pivotally mounted on said bracket, a work engaging member pivotally mounted on said arm for movement upwardly and downwardly and means carried by the bracket constructed and arranged to maintain the work engaging surface of said work engaging member normally in substantially the 85 same horizontal plane in different adjusted positions of said work engaging member.

19. In a machine of the class described, 90 work positioning means comprising a frame, a bracket carried by said frame, a work engaging member carried by said bracket for movement upwardly and downwardly, means for adjusting said work engaging member and a cam member mounted on 95 said bracket constructed to maintain the work engaging surface of said work engaging member normally in substantially the same horizontal plane in different adjusted positions of said member.

20. In a machine of the class described, 100 a frame, means on said frame for positioning a shank piece, a bracket mounted adjustably on the frame, means for indicating the position of adjustment of the bracket relatively to the frame, a shoe positioning member 105 carried by the bracket, means for adjusting the shoe positioning member on the bracket, and means for indicating the position of adjustment of the shoe positioning member relatively to the bracket, said indicating 110 means being arranged to mark the positions of adjustment of the shoe positioning member relatively to the frame and the shank-piece positioning means appropriate to shoes of various sizes and styles. 115

21. In a machine of the class described, 120 a frame, shank piece attaching means carried by said frame, and means mounted on said frame independent of said attaching means for supporting a shank piece in predetermined position relatively to said attaching means.

22. In a machine of the class described, 125 a frame, shank piece attaching means carried by said frame, and means for supporting a shank piece independently of said attaching means comprising springs mounted on said frame and constructed and arranged

- for the insertion of the end of the shank piece between them.
23. In a machine of the class described, a frame, shank piece attaching means carried by said frame, devices mounted on said frame and constructed and arranged to support a shank piece, and means carried by said frame in advance of said shank piece attaching means constructed and arranged to position the shank piece supported by said devices in predetermined relation to the shank piece attaching means.
24. In a machine of the class described, a frame, shank piece attaching means carried by said frame, and shank piece positioning means mounted on the frame rearwardly of said attaching means and constructed and arranged to position the shank piece independently of the attaching means.
25. In a machine of the class described, a frame, shank piece attaching means carried by said frame, means for positioning a shank piece at its forward end, and means for positioning the shank piece constructed and arranged to engage the shank piece adjacent to its other end.
26. In a machine of the class described, means for attaching a shank piece to a shoe, means for positioning the shank piece longitudinally of the shoe, and means for positioning the shank piece laterally of the shoe.
27. In a machine of the class described, means for attaching a shank piece to a shoe, means for positioning the shank piece longitudinally of the shoe, and means for positioning the shank piece laterally of the shoe, said last-mentioned means being constructed and arranged to permit lateral movement of the shank piece relatively to said attaching means.
28. In a machine of the class described, a frame, mechanism carried by the frame for operating on a shoe, and means mounted on the frame and disposed for engagement with the end face of a shank piece to position it relatively to the operating mechanism and the shoe.
29. In a machine of the class described, means for operating on a shoe having a shank piece loosely superposed thereon, and means for positioning the shank piece relatively to the operating mechanism.
30. In a machine of the class described, a frame, means carried by the frame for positioning a shank piece loosely superposed on a shoe, and means mounted on the frame for attaching the shank piece to the shoe.
31. A device for facilitating the attachment of shank members in the manufacture of shoes comprising a frame and a gage member adjustably carried thereby constructed and arranged to form an abutment for the forward portion of a shank member to position it with respect to a shoe to which it is to be attached.
32. A device for facilitating the attachment of shank members in the manufacture of shoes comprising a frame constructed and arranged to have a shoe presented thereto for attachment of a shank piece to the shoe, and a gage member forming an abutment to position a shank member loosely superposed upon the shoe so as to locate the forward extremity of the shank member at the break between the shank portion and the forepart of the sole of the shoe.
33. A shank positioning device comprising a frame to which a shoe may be presented and a yielding gage member carried by said frame arranged to engage an extremity of a shank member to position the same during its attachment to a shoe.
- In testimony whereof I, the said FRED L. AYERS, have signed my name to this specification.
- FRED L. AYERS.
- In testimony whereof I, the said FRED L. MACKENZIE, have signed my name to this specification.
- FRED L. MACKENZIE.
